(57) **CLAIM**

The ornamental design for a diagnostic apparatus for medical or laboratory use, as shown and described.

DESCRIPTION

Figure 1.1 is a perspective view of a diagnostic apparatus for medical or laboratory use;

Figure 1.2 is another perspective view thereof;

Figure 1.3 is a front view thereof;

Figure 1.4 is a rear view thereof;

Figure 1.5 is a top view thereof;

Figure 1.6 is a hoiorn view thereof;

Figure 1.7 is a side view thereof; and

Figure 1.8 is another side view thereof.

The broken lines and broken line areas shown in Figures 1.1-1.8 illustrate portions of the diagnostic apparatus for medical or laboratory use that form no part of the claimed design.
